UNITED STATES PATENT OFFICE

FRED WIDOE, OF OMAHA, NEBRASKA

RECORDING AND ADVERTISING DEVICE

Application filed March 22, 1929. Serial No. 349,210.

This invention relates to a device for recording the distance traveled or to be traveled by a vehicle to determine when a new supply of lubrication will be required.

5 In the use of automobiles new lubrication is required when approximately five hundred miles have been driven to prevent undue wearing of the bearings, and various recording devices more or less efficient have been employed and carried by the automobile as a reminder to the driver so that relubrication will not be neglected.

10 One of the objects of the invention is to provide a recording device which may be readily and conveniently adjusted for indicating a predetermined distance. Another object is to provide a device for the purpose described which may be produced at a nominal expense, may be quickly adjusted and carried in a car.

15 The invention includes a device adapted for advertising, and is of particular advantage in this respect since it may exhibit the name of a producer of oils and gasoline for holding and 20 extending trade to consumers, the latter being benefited by use of the device.

25 While the recording and advertising device may be used for other purpose it has been found to be of particular advantage for the uses mentioned. It is so inexpensive in manufacture that it is furnished free to car owners by dealers in oil and gasoline.

30 With the foregoing objects in view the invention presents a new and useful construction, combination and arrangement of parts as described herein and claimed, and as illustrated in the accompanying drawing, wherein,

35 Fig. 1 is a view of the front side of the device when folded. Fig. 2 is a rear view of the same, the elastic loops being removed and the device being inverted. Fig. 3 is a view of the inner sides of the device when unfolded. Fig. 4 is a view showing one of the sides of a recording strip. Fig. 5 illustrates the reverse side of the strip shown in Fig. 4.

40 Referring now to the drawing for a more particular description, I provide a front leaf 45 6 and a rear leaf 7 each being provided mid-

way between the side-edges with an aperture 8.

As shown in Fig. 3 of the drawing the two leaves mentioned are joined and may be folded on the dotted line to dispose the apertures 8 in register and may be pressed against each other by elastic bands 9 shown in Fig. 1, the apertures 8 being of advantage to permit the device to be hung upon a hook (not shown) upon the dash board or other part of an automobile convenient for inspection. However the leaves 6 and 7 if desired may consist of separate cards corresponding in size and form and may be held together by the elastic bands mentioned with said apertures 8 in register. Notches α are formed in the edges of the leaves for receiving the bands 9.

45 In the use of the device the leaves 6 and 7 are normally disposed with their inner sides in engagement and the front and rear sides 50 when disposed in folded relation, are used for inspection and adjustments, and it will be understood that the device when inspected is disposed in the position shown in Fig. 1 of the drawing and that, when adjustments are 55 to be made, the end of the device provided with apertures 8 is swung toward the operator, and when the device has been swung approximately a half circle in the direction mentioned the parts upon the rear side may 60 be inspected or adjusted.

65 Numerals 10 indicate flexible strips each provided with numerals 11 on one of its sides and numerals 12 on its opposite side, the numerals 12, of course, being inverted relative to the numerals 11 so that they will appear in upright readable positions after the device has been inverted.

70 The leaf 7 is incised to provide a pair of rows of slots 13 and a pair of rows of slots 14, these slots being formed transversely of the leaf, and disposed approximately parallel with reference to each other, and threaded in the slots of the rows 13 and 14 are the strips 10, and while only four strips are shown in 75 Fig. 2 of the drawing, for recording a distance less than 10,000 miles, it is obvious that a greater number of strips could be employed, if desired, and operation would be the same.

80 A window is formed in the leaf 6, said 100

window being provided by use of apertures 15, these being disposed in alignment transversely of said leaf, the distance of these apertures from each other corresponding to the distance apart of the strips 10, and it will be understood that these strips may have sliding movements in their slots to register any desired number less than 10,000 to indicate the number of miles traveled or to be traveled, 10 said number appearing at the apertures 15.

10 The flexible slide-strips gently resist sliding movements through their slots, but by grasping an end-portion of a strip with a thumb and finger, an operator may readily adjust 15 the strips for registration of said numbers, and on account of the construction described the particular number registered by use of the strips 10 will appear at the apertures 15.

Numeral 16 indicates a sight-line which is 20 disposed transversely across the leaf 7 said line being for use of the operator and disposed closely adjacent to and at right angles to the rows 14 of slots.

25 Operation of the device will now be described, and for this description it is assumed that the lubricant should be changed for each 500 miles of travel. At the time the driver replenishes his car with a lubricant, and assuming that the speedometer registers 7154 miles he, by moving the slide-strips, causes the number 7654 to appear upon the leaf 7 adjacent to the sight-line 16 and, as described, this last named number will also appear at the apertures 15.

35 The device is then placed where it may be compared with the numbers recorded by the speedometer, to serve as a warning or reminder, and when the number of miles recorded by the speedometer equals the number exhibited by the device, the driver will 40 know that a new lubricant should be supplied.

45 Numeral 17 indicates a space reserved for the use of advertising, this being an important feature, and being for the use of a producer or dealer of oils, greases and gasoline as explained.

50 While I have shown and described details of construction as one embodiment of the invention, I do not wish to limit myself in this respect, and changes may be made in form, size, proportion of parts and minor details, said changes being determined by the scope of the invention as claimed.

55 Since a part of each flexible strip is disposed between the leaves it is necessary that identical numerals at the respective sides of a strip shall be disposed in planes adjacent to each other as shown in Figs. 4 and 5 of 60 the drawing. For instance, the numeral "7" exhibited at the window shown in Fig. 1 because that side of the flexible strip exhibiting said numeral is disposed between the leaves, and the corresponding numeral 65 "7" on the opposite side of the flexible strip

is exhibited, as shown in Fig. 2, since it is disposed in an adjacent plane.

I claim as my invention,—

1. In a device for the purposes described, a leaf having a window, a second leaf pressed against the first leaf and provided with slots, a plurality of flexible approximately parallel strips each bearing numerals on its opposed sides and disposed on the second leaf with parts thereof engaging in said slots to exhibit a selected numeral on the second leaf and to exhibit a corresponding numeral at said window. 75

2. In a device for the purposes described, a leaf having a window, a second leaf having slots arranged in pairs transversely thereof and pressed against the first named leaf, a plurality of flexible strips bearing numerals on their respective sides, the numerals on one of said sides corresponding to the numerals upon the other side, each strip being disposed on the second leaf to exhibit a selected numeral and having a part disposed between said leaves to exhibit a numeral at said window. 80

3. In a device for the purposes described, a leaf provided with a window, a second leaf in engagement with the first named leaf, a plurality of strips each bearing numerals on its opposed sides and having parts disposed on the outer side of the second leaf to exhibit a selected numeral and having a part disposed on the inner side of the second leaf to exhibit a numeral, corresponding to said selected numeral, at said window. 95

4. In a device for the purposes described, a leaf having a window and provided with notches, a second leaf provided with notches, elastic bands in said notches for pressing the leaves against each other, and a plurality of flexible strips provided with numerals on their opposed sides, each having a part disposed on the second leaf to exhibit a selected numeral and having a part disposed between the leaves to exhibit a numeral corresponding to said selected numeral at said window. 105

5. In a device for the purposes described, a leaf having a window, a second leaf pressed against the first named leaf, a plurality of flexible strips each having numerals on one of its sides and provided on its opposite side with inverted secondary numerals corresponding to said first named numerals, each strip having a part disposed on the second leaf for exhibiting a selected numeral and having a part disposed between said leaves for exhibiting a numeral corresponding to said selected numeral at said window. 115

6. In a device for the purposes described, a leaf provided with a window, a second leaf pressed against the first named leaf, a plurality of flexible strips provided on their opposed sides with numerals, each strip having a part disposed on the second leaf to 125

exhibit a selected numeral and having a part disposed between said leaves to exhibit a numeral corresponding to said selected numeral at said window, said leaves being provided with apertures adapted to be disposed in register relative to each other.

7. In a device for the purposes described, a leaf having a window, a second leaf provided with a sight-line transversely thereof, a plurality of flexible strips each bearing numerals on its opposed sides and movable on the second leaf at right-angles to the sight-line to exhibit a selected numeral closely adjacent to said line and having a part disposed between said leaves to exhibit a numeral corresponding to said selected numeral at the window of said first named leaf.

20 In testimony whereof, I have affixed my signature.

FRED WIDOE.
